UNITED STATES PATENT OFFICE.

SAMUEL M. COZAD, OF LOS ANGELES, CALIFORNIA.

LIQUID-DISPENSING DEVICE.

Application filed October 12, 1922. Serial No. 593,970.

To all whom it may concern:

Be it known that I, SAMUEL M. COZAD, a citizen of the United States, residing at Los Angeles, in the county of Los Angeles and State of California, have invented new and useful Improvements in Liquid-Dispensing Devices, of which the following is a specification.

My invention relates to liquid dispensing devices, and a purpose of my invention is the provision of a device of this character by means of which the dispensing of a liquid in predetermined quantities can be automatically effected, the invention in its present embodiment being particularly adapted, although not necessarily, for the dispensing of bleaching liquids as used in laundries.

Although I have shown and described only one form of liquid dispensing device embodying my invention, and will point out the novel features thereof in claims, it is to be understood that various changes and modifications may be made without departing from the spirit of the invention and the spirit and scope of the appended claims.

In the accompanying drawings,

Figure 1 is a view showing in side elevation one form of liquid dispensing device embodying my invention;

Figure 2 is a top plan view of the device shown in Figure 1;

Figures 3 and 4 are vertical sectional views taken on the line 3—4 of Figure 1 and showing detached parts of the device;

Figure 5 is a fragmentary detail perspective view of the pivot means for the receptacle supporting lever.

Similar reference characters refer to similar parts in each of the several views.

Referring specifically to the drawings, and particularly to Figure 1, my invention, in its present embodiment, is shown as comprising a hollow casing 15 which communicates at its lower end with a connecting nipple 16 screw threaded for the purpose of providing a connection between a tank adapted to contain and from which any liquid such as bleaching liquid is adapted to be dispensed. Communicating with the side of the casing 15 is a pipe 17 having a discharge nozzle 18. The pipe 17 is formed with upstanding ears 19 provided with segmental openings 20 through which is extended a pivot bar or pin 21. As clearly shown in Figure 5, the pivot bar 21 is of substantially

triangular form in cross section to provide a relatively sharp edge 22 which is adapted to contact with the lower corners of the segmental openings 20 to provide a pivot upon which the bar is adapted to rock. For the purpose of confining the bar 21 against longitudinal shifting within the openings 20, a screw 23 is threaded in one end of the bar so as to engage a washer 24, as clearly shown in Figures 2 and 5.

A lever 25 is rigidly secured to the bar 21 at a point between the ears 19 so that the edge 22 of the bar functions as a pivot point about which the lever 25 is adapted to swing. One end of the lever 25 is bent downwardly and terminates in a hook 26, upon which latter a bail 27 of a bucket or other suitable receptacle 28 is adapted to hang for supporting the receptacle in receiving position with respect to the discharge nozzle 18. The opposite end of the lever 25 is adapted to slidably receive a weight 29 provided with a set screw 30 for locking the weight in any desired position along the length of the lever. For the purpose of preventing distortion of the lever and eliminating the noise incident to the return of the lever to its normal position, a bumper 31 is secured to the side of the casing 15 so as to project above the upper end of the casing and to be engaged by the lever as it swings downwardly. This bumper is preferably formed of rubber or other suitable material and is slotted to accommodate a projection 32 (Figure 4), to which latter is secured a guide rod 33. The guide rod 33 is bent at its upper end to provide a hook 34, and this rod is associated with the lever 25 so as to guide the latter during vertical movement with the hook limiting the upward swinging movement of the lever.

As clearly shown in Figure 4, the casing 15 is provided with a valve chamber 35 and a discharge chamber 36 provided with a discharge opening 37 which communicates with the pipe 17. The walls of the chambers 35 and 36 are separated by an annular flange 38 which is adapted to form a seat for a shoulder 39 of a subsidiary casing 40. This casing 40 is provided at its lower end with a port 41 controlled by a valve 42. With the casing 40 applied to the casing 15, it is disposed within the chamber 36, with the valve disposed in the chamber 35. The casing 40 is provided with an annular flange 43 which is adapted to be bolted or otherwise secured

to a corresponding flange 44 formed on the casing 15 so as to provide a cover for the casing and to close the upper end of the chamber 36.

- 5 The valve 42 is adapted to control the flow of liquid from the chamber 35 to the port 37, and this valve is provided with a stem 45 which is threaded to receive nuts 46 for securing a deflecting plate 47 thereon. The 10 upper end of the stem 45 is connected to a plug 48 mounted for vertical movement within a socket 49 formed on the upper end of the casing 40. The deflecting plate 47 is designed for the purpose of directing the 15 liquid entering the casing 40 through the port 41 toward the port 37 and subsequently into the pipe 17. In this manner, the possibility of leakage between the plug 48 and the socket 49 is prevented.
- 20 As shown in Figure 3, the hooked end 34 of the guide bar 33 is extended downwardly in parallel relation to the guide bar and into engagement with the flange 43. At this point the guide bar is bent at right angles 25 to provide a lip 50 which merely contacts with the flange 43.

For actuating the valve 42, the lever 51 is extended through an opening 52 formed in the socket 48, and as shown in Figure 1, 30 this lever is adapted to be operatively connected to the lever 25 through the medium of latching means. This latching means in the present instance comprises a latching tongue 53 formed on the lever 25 and adapted 35 to engage a latching plate 54 pivotally sustained upon the lever 51 by means of a pivot pin 55. The arrangement of the lever and plate is such that the lever normally engages the plate to hold the lever 51 in 40 substantially horizontal position wherein the valve 42 is open. The degree of movement of the lever 51 is adapted to be regulated by means of a weight 56 adjustably mounted on the lever and adapted to be locked 45 in any adjusted position by means of a set screw 57.

The operation of the dispensing device is as follows: Liquid supplied to the casing 15 from the tank, not shown, is adapted to 50 be discharged into the receptacle 28 when the valve 42 is open. In the open position of the valve 42, the lever 51 is latched in horizontal position by the latch member 53 engaging the latch plate 54, all as clearly 55 shown in Figures 1 and 2. A weight 29 of the lever 25 is adjusted to counterbalance the lever until the liquid discharged into the receptacle 28 reaches a predetermined quantity. When this occurs, the weight of 60 the liquid overbalances the weight of the lever and weight 29, thereby causing the lever to swing upwardly about the pivot bar 21 as a center to move the latch member 53 out of engagement with the latch plate 54.

65 Under the action of the weight 56 the lever

51 is now free to swing upwardly about the pivot point 58, thereby moving the head 48 upwardly within the socket 49 and thus causing the valve 42 to close the port 41. With the port 41 closed, the supply of liquid 70 to the receptacle is discontinued, and with the receptacle containing the predetermined quantity of liquid.

In order to reset the dispensing device, the latch plate may be manipulated by virtue 75 of its pivotal mounting to again engage the latch member 53, it being understood that it is first necessary to restore the levers 25 and 51 to the positions shown in Figure 1.

I claim as my invention:

1. A main receptacle supporting lever, counter-balancing means adjustable on the main lever, a pipe for supplying liquid to the receptacle supported by the main lever, a valve for controlling the passage of liquid 85 through the pipe, a second lever for actuating the valve, counter-balancing means adjustable on the second lever, and latching means for connecting the main and second levers in position with the valve open and the counter-balancing means ineffective to actuate the second lever and close the valve until a pre-determined quantity of liquid has been supplied to the receptacle to overbalance the counter-balancing means and release the latching means and allow the second lever to be operated by its counter-balancing means and close the valve to discontinue the supply of liquid to the receptacle. 90

2. A liquid dispensing device comprising 100 a casing adapted for connection with a liquid supply means, a discharge pipe communicating with the casing, a valve for controlling the passage of liquid through the casing and to the discharge pipe, a lever fulcrumed on the discharge pipe, a receptacle supporting means formed on the lever for sustaining the receptacle in receiving relation with respect to the discharge pipe, a weight adjustable on the lever for counterbalancing the weight of the receptacle and a predetermined quantity of liquid discharged into the receptacle, a lever for normally closing said valve, and latching means controllable by the first lever in such manner that 115 when the first lever is overbalanced, said latching means will release the second lever to allow the valve to move to closed position.

3. A liquid dispensing device comprising 120 a casing adapted for connection with a liquid supply means, a discharge pipe communicating with the casing, a valve for controlling the passage of liquid through the casing and to the discharge pipe, a lever fulcrumed on the discharge pipe, a receptacle supporting means formed on the lever for sustaining the receptacle in receiving relation with respect to the discharge pipe, a weight adjustable on the lever for counterbalancing 125 130

the weight of the receptacle and a predetermined quantity of liquid discharged into the receptacle, a socket formed in the casing, a plug movable within the socket and 5 operatively connected to said valve, a lever fulcrumed on the casing and connected to said plug, means for normally urging the last mentioned lever to a position from which said plug is elevated to close said 10 valve, and latching means connecting the two levers for normally holding the first lever to maintain said valve in open position and to release said lever when the first lever is moved against the action of said 15 weight.

4. In a liquid dispensing device, a re-

ceptacle supporting lever normally urged to one position, a bumper adapted to be engaged by said lever when the latter is moved to its urged position, a guide for said lever 20 operating to limit the urged position thereof, a valve actuating lever normally urged to a position in which said valve is closed, and latching means connecting the levers comprising a latch member fixed to the first 25 lever, and a latch plate pivoted on the second lever and adapted to be engaged by said latch member.

In testimony whereof I have signed my name to this specification.

SAMUEL M. COZAD.
